UNITED STATES PATENT OFFICE.

OSWALD SILBERRAD, OF BUCKHURST HILL, ENGLAND.

EXPLOSIVE.

1,102,964.

Specification of Letters Patent.

Patented July 7, 1914.

No Drawing. Original application filed June 3, 1912, Serial No. 701,242. Divided and this application filed November 23, 1912. Serial No. 733,196.

To all whom it may concern:

Be it known that I, OSWALD SILBERRAD, Ph. D., a subject of the King of Great Britain and Ireland, director of the Silberrad Research Laboratories, and residing at Buckhurst Hill, in the county of Essex, England, have invented certain new and useful Improvements in Explosives, of which the following is a specification.

10 This invention relates to the manufacture of explosives, and has for its object to produce a plastic explosive by means of liquid nitrated hydrocarbons obtained by nitrating a liquid neutral product of coal tar, boiling between about 200° C. and 350° C. The nitrated products for use in the explosive can be produced from any or all or any liquid neutral fraction of the following coal tar products, viz.,—the oils boiling between 15 about 200° C. to about 350° C., that is to say, the liquid portions of middle heavy and anthracene oils, the residues from the manufacture of carbolic acid, creosote, naphthalene and anthracene, and also coal tar lubricating oil. The oils preferably used are those of which at least the greater portion boils between 200° C. and 270° C. The nitrating is effected as described in my application for Letters Patent Ser. No. 701,242, filed June 3rd, 1912, of which this application is a division.

I have found that by taking that fraction of tar (or of any of the oils or residues obtained in the industrial treatment of tar) 35 which boils at 200° C. to 270° C. or thereabout, and subjecting it to the treatment set forth below, I obtain a product which on nitration under suitable conditions yields a nitro product which not only is liquid, but 40 is also nonvolatile, and which thus enables me to produce the long sought for product, viz., an explosive which is plastic and permanent under all conditions without the aid of nitroglycerin. The nitration of the 45 liquid fraction of coal tar selected, which consists chiefly of methylated naphthalenes, yields this liquid nitro-product which consists essentially of nitro derivatives of methylated naphthalenes. The product contains mono-nitro and di-nitro methylated naphthalenes, the quantity of each depending to the extent to which the nitration is carried. This new technical product 50 consists essentially of nitro derivatives of the various isomers of methyl and dimethyl-

naphthalene. Not only is this product itself non-volatile and liquid, but being essentially composed of derivatives of the naphthalene series, it is capable of dissolving a large quantity of highly nitrated compounds of 60 the benzene series (as trinitrotoluene) which are of themselves solids, and as the final solution remains liquid, it is particularly suitable for the manufacture of safe plastic explosives of great power and quite permanent. 65

In manufacturing an explosive according to one example, a suitable still is charged with the creosote oil, containing the residue from the manufacture of carbolic acid and naphthalene, and that fraction is collected boiling from 200° C. to 270° C. After freeing the distillate from any naphthalene which separates out, it is subjected to chemical washing with alkali and acid, using 70 sufficient alkali to remove all phenolic bodies in the first place, then water, then sulfuric acid, then dilute alkali, and finally water again.

In effecting the washing, I find it convenient to subject the oil to a thorough washing with 2½% to 5% concentrated oil of vitriol, and to repeat this operation until the desired degree of purity is obtained, 80 2.5% to 20% of acid being used in this manner. 85

The washing with concentrated sulfuric acid serves to remove hydrides, as for example, hydro-naphthalene derivatives, ace-naphthalene, and anthracene derivatives of 90 the acetylene series and other unsaturated and unstable substances, which I have found are present in this product from coal tar and which react with violence on nitration and become oxidized. After washing, the 95 oil is again distilled, and the fraction boiling between 200° C. and 270° C. again collected, allowed to stand and freed from any further quantity of naphthalene which separates. The oil is now ready for nitration, 100 in order to effect which I proceed as follows:

The nitration may be carried out as follows:—1000 parts by volume of oil prepared as above boiling between 200° C. and 260° C. is run into a suitable nitration vessel fitted with agitator and cooling jacket. A mixture of 100 parts by volume of nitric acid of 1.5 sp. gr. with 25 parts of water are gradually run in. Then 100 parts by volume of nitric acid of sp. gr. 1.5 previ- 110

ously diluted with 10 parts of water are gradually added. Then 100 parts by volume of nitric acid 1.5 sp. gr. previously diluted with 5 parts of water are gradually added. Then 100 parts by volume of nitric acid of 1.5 sp. gr. is gradually added; and finally 150 parts by volume of nitric acid of 1.5 sp. gr. previously mixed with 450 parts by volume of concentrated sulfuric acid are gradually added.

During the whole operation the contents of the vessel are kept under violent agitation, and the temperature preferably maintained between 20° C. and 35° C. during addition of acid. The mixture is allowed to stand over-night, and is then gradually warmed to 60° C. to 70° C. under stirring.

In cases where very effective purification is required the following method may be adopted:—The nitrated oil is first stirred with a weak solution say 5% of soda-ash, preferably at about 50° C. to 70° C. for a period of about 12 to 24 hours. It is then separated, washed with water, and run into a suitable vessel containing clean water, preferably about 10 times its bulk, and also a few lumps of marble or the like are added, and the mixture gently boiled under the reflux condenser until all unstable compounds are decomposed. This is generally satisfactorily accomplished in from 24 to 48 hours.

Instead of soda-ash I may use the carbonates or bicarbonates or hydroxids of any of the alkali metals or mixtures containing any or all of these; similarly in place of marble I may use chalk, dolomite, magnesia or the carbonates or hydroxids of any or all of the alkaline earths.

In producing an explosive by the use of the nitrated product so produced, a suitable quantity of soluble nitrocellulose or collodion cotton is added, gelatinization is effected by the aid of heat, and a suitable proportion of oxygen bearing salts is added. If desired, highly nitrated compounds of the benzene series, such as crude tri-nitro toluene may be added in comparatively large quantities for the nitrated product being a derivative of the naphthalene series is capable of dissolving a comparatively

large quantity of these highly nitrated compounds of the benzene series.

The following is an example of an explosive made according to my invention:

	Parts.
Nitro hydrocarbons as described above	10
Highly nitrated compounds of the benzene series (as crude di and tri-nitro toluene)	20
Soluble nitro-cellulose or collodion cotton	60
Oxygen-bearing salts as potassium chlorate	0.5
With or without preservatives or wood meal	70
	65

For this purpose, I find the following oxygen-bearing salts suitable:—The nitrates and perchlorates of potassium, sodium or ammonium, the chlorates of potassium or sodium, or any mixture of these; but I find it desirable to avoid any mixture containing a chlorate together with an ammonium salt, as I find such a combination is likely to become unstable.

Similarly, the nitro hydrocarbons above described may be utilized with other explosives.

What I claim is:

1. A plastic explosive containing as an ingredient a liquid nitro product consisting essentially of nitro-derivatives of methylated naphthalenes, as set forth.

2. A plastic explosive containing as an ingredient a liquid nitro product consisting essentially of dinitro derivatives of methylated naphthalenes, as set forth.

3. A plastic explosive containing the following ingredients, viz., liquid nitro derivatives of methylated naphthalenes, highly nitrated hydrocarbons of the benzene series, soluble nitro-cellulose, and oxygen bearing salts, as set forth.

In testimony whereof I have signed my name to this specification in the presence of two subscribing witnesses.

OSWALD SILBERRAD.

Witnesses:

J. W. PALCHING,
E. C. THORP.
